UNITED STATES PATENT OFFICE.

JOHN HENRY PAUL HANEKLAUS, OF POMEROY, IOWA.

ICE TRAY.

Application filed March 15, 1926. Serial No. 94,853.

This invention relates to ice trays and has for its primary object to provide means whereby ice may be carried from place to place by pulling the tray over the surface of the ground, the same being supported by casters or other suitable rollers whereby the block of ice may be lifted by the tray and conveniently disposed within an ice box or other place of deposit, without the ice man's hands actually coming into contact with the ice and for overcoming the requirement of carrying the ice by means of ice tongs which are very unsatisfactory, the ice frequently becoming loose from the same and falling upon the foot of the carrier and necessitating the transportation of the ice by use of but one hand.

A further object of the invention is to provide a tray that is so constructed as to enable the ice man to carry the ice from place to place in both hands, for thus greatly reducing the burden and negativating the liability of the ice dropping.

A still further object of the invention is to provide means as a part of the tray whereby the ice will be prevented from slipping therefrom even though the tray is tilted a considerable degree, said means being operable to position out of engagement with the ice in order to permit the removal of the ice from the tray whenever such is the desire.

Other objects will become apparent as the nature of the invention will be better understood, the same comprising the novel form, combination and arrangement of parts hereinafter more fully described and shown in the accompanying drawings and claimed.

In the drawings wherein like reference characters indicate corresponding parts throughout all of the views:

Figure 1 is a top plan view of my improved tray,

Fig. 2 is a side elevation thereof,

Fig. 3 is detail transverse cross section,

Fig. 4 is a perspective of a sliding bar member provided as a means for the operation of the ice engaging prongs which are carried by spaced horizontal bar members mounted for limited rotation in reverse directions within the frame, which prongs bite into the ice disposed upon the tray in order that the ice will not slide thereon even though the tray be tilted at an angle, and

Fig. 5 is a reduced front end elevation of

the tray having associated therewith a shoulder harness in order that the shoulders of the ice man may be brought into use for the lifting and carrying of the ice upon the tray.

Now having particular reference to the drawing, my novel tray constitutes the provision of a frame 5 of square or rectangular shape and being constructed of L-iron bars as more clearly disclosed in Figs. 1, 3 and 5. Upon the under side of the frame and at the four corners thereof are supporting casters 6 in order that the tray may be conveniently pushed from place to place especially when not in use. The frame further constitutes the provision of a transversely extending cross bar 7 also of angle iron construction and at the center of the tray as clearly shown in Fig. 1.

Extending longitudinally of the frame are spaced parallel circular hollow bars 8 that are arranged within openings in the central bar 7 and the forward side bar of the frame, and also within spaced openings in an auxiliary plane bar 9 secured at its opposite ends to the sides of the frame in slightly spaced relation with the end bar thereof as clearly shown in Fig. 1. Throughout the length of these bars upon the top side thereof are spaced ice engaging prongs 10, while formed upon the under side of each bar directly in the center thereof is a depending prong 11, as shown in Fig. 3.

Extending transversely across the under side of the frame directly beneath the central bar 7 thereof, is a flat bar 12 that is slidably guided at its opposite ends within brackets 13-13 secured to the under sides of the frame side bars as disclosed in Figs. 2 and 3. Said bar 12 is formed throughout its length with spaced slots 14 within which engage the pendent tongs 11 of said bars 8 and obviously by moving the bar 12 in opposite directions, the bars 8 will be rotated for moving the ice engaging tongs 10 into or out of position with respect to a block of ice A, Fig. 3, disposed upon the tray.

Upon the side bars of the frame are spaced ears 15 that are formed with openings for permitting the pivotal attachment of bail-like carrying handles 16. One of the handles 16 is so formed as to provide between its respective securing ears a pair of spaced downwardly extending fingers 17

2
 between which the adjacent end of the sliding bar 12 is loosely pivotally secured as at 18. This end of said bar is turned at right angles to the bar for providing a pivotal 5 attaching ear 19 that is formed with an opening for receiving the pivotal connection 18, said fingers 17 of the respective carrying bail 16 being slotted for allowing the pivot to move therein during the actuation of the 10 slide bar 12 through movement of said bail in reverse directions upon its pivotal support with the frame.

If desired, a shoulder strap 20 may be provided for engagement over the shoulders 15 around the neck of the ice man in order that the tray and ice supported thereon may be suspended from the shoulders if desired. This strap is provided at its opposite ends 20 with snap hooks 21 for detachable engagement with the carrying bails 16, as shown in Fig. 5.

Extending outwardly from the front bar of the frame 5 is a pair of spaced arms 22 in order that the front edge of the tray may 25 be supported upon a platform or the ice compartment of a refrigerator for facilitating the tilting of the tray which will permit the ice to slide onto the platform or 30 into the box after the prongs 10 have been disengaged from the ice by movement of the proper bail 16 in the direction of the arrow in Fig. 3.

It will thus be seen that I have provided a highly novel, simple and efficient form of 35 ice tray that is well adapted to all of the purposes heretofore described, and even though I have hereinbefore designated and even though I have shown and described the most preferred embodiment of the invention 40 with which I am at this time familiar, it is nevertheless to be understood that minor changes may be made therein without affecting the spirit and scope of the appended claims.

45 Having thus described my invention, what

I claim as new and desire to secure by Letters Patent is:—

1. In an ice tray of the character described, a supporting frame, ice engaging prongs throughout substantially the entire 50 area of the frame for preventing the sliding of the ice on the tray, and means for moving the prongs into position out of engagement with the ice to permit the ice to be readily removed from the tray. 55

2. In an ice tray of the character described, a frame construction, a plurality of spaced bars rockably mounted within the frame, prongs upon the top sides of the bars for engagement with the ice disposed thereon, and means for rocking the bars within the frame for disengaging the prongs from the ice. 60

3. In an ice tray of the character described, a frame, a pair of carrying handles, 65 bar members journaled for rocking movement within the tray, ice engaging prongs carried by said bars for engaging the ice and preventing the same from sliding upon the tray, and means operable by one of the 70 carrying handles for so rocking the bars as to disengage the prongs from the ice.

4. In an ice tray of the character described, a supporting frame, carrying handles for the frame, ice engaging prongs 75 arranged throughout substantially the entire area of the frame for engagement with the ice in preventing the slipping of the same upon the tray, and means operable by one of the carrying handles for disengaging the 80 prongs from the ice.

5. In an ice tray of the character described, a tray, a plurality of spaced parallel bar members rockably mounted within the tray, ice engaging prongs carried by said 85 bars and means for rocking the bars in opposite directions for moving said prongs into or out of ice engaging position.

In testimony whereof I affix my signature.

JOHN HENRY PAUL HANEKLAUS.
